UNITED STATES PATENT OFFICE.

EDWARD D. BENNINGHOFF, OF CRESTON, IOWA.

DESIGN FOR A CHURN-LID.

SPECIFICATION forming part of Design No. 27,814, dated November 2, 1897.

Application filed September 8, 1897. Serial No. 650,992. Term of patent 7 years.

To all whom it may concern:

Be it known that I, EDWARD D. BENNINGHOFF, of Creston, in the county of Union and State of Iowa, have invented and produced a new and original Design for a Churn-Lid, of which the following is a full, clear, and exact description.

The invention relates to churning having a revoluble dasher within a tub adapted to be covered by a lid, the subject of the present design.

Reference is to be had to the accompanying drawing, forming a part of this specification, in which the figure is a perspective view of a churn-lid, showing my design.

The leading feature of the design consists of a disk A, from which rises an inverted-U-shaped bracket B, terminating at its ends in

outward flanges B', lying flat on the upper surface of the disk A.

Minor features are provided in that the terminal ends of the flanges project beyond the peripheral surface of the disk A, and the said ends are notched, as at B'', and on the top surfaces of the flanges appear nuts C.

Further minor features are the vertically-aligned apertures B³ and A' in the disk A and the bracket B, the aperture A' appearing countersunk on the top of the disk, as shown.

I claim—

The design for a churn-lid as herein shown and described.

EDWARD D. BENNINGHOFF.
